United States Patent Office

Des. 216,269
Patented Dec. 9, 1969

216,269

GOBLET

Ben Seibel, New York, N.Y., assignor to Fostoria Glass
Company, Moundsville, W. Va.

Continuation-in-part of design application Ser. No.
10,437, Feb. 5, 1968. This application Dec. 4, 1968,
Ser. No. 15,031

Term of patent 14 years

Int. Cl. D7—01

U.S. Cl. D36—8

FIG. 1

FIG. 2

FIG. 3

FIG. 4

FIGURE 1 is a side elevational view of the goblet illustrating my new design;

FIGURE 2 is a vertical section thereof taken along the line 2—2 of FIGURE 3;

FIGURE 3 is a bottom plan view; and

FIGURE 4 is a developed plan view of the ornamentation.

This is a continuation-in-part of application Ser. No. D. 10,437 filed Feb. 5, 1968 and now abandoned.

I claim:

The ornamental design for a goblet, as shown and described.
